CLOCK

Arno W. Fowler, Highland, Ill.

Application March 13, 1930, Serial No. 435,615

7 Claims. (Cl. 200—36)

This invention relates to clocks and more particularly to timing mechanism for operating an electric switch to close a power circuit operating a radio receiving set.

5 In its broader aspect the object of the invention is to provide timing mechanism for operating an electric switch which will be simple of construction, economical to manufacture and simple in control.

10 In its narrower aspect the object of the invention is to provide a clock which may be mounted in connection with a radio receiving set and which will operate suitable mechanism for closing the power supply circuit for the set 15 at a predetermined time.

Other objects will appear from the following detail description taken in connection with the accompanying drawings, in which:—

20 Fig. 1 is a front elevation of a radio cabinet showing the control panel with the device mounted thereon.

25 Fig. 2 is a front elevation of the clock mechanism with the dial, stationary contact member and setting mechanism removed, and showing diagrammatically the electrical circuits involved.

Fig. 3 is a side elevation of the clock mechanism shown in Fig. 2.

30 Fig. 4 is a side elevation partly in section of the dial, stationary contact member, setting mechanism and a rotating contact member.

Fig. 5 is a rear elevation of the stationary contact member.

35 A radio cabinet 1 of conventional construction has a control panel 2 which supports the usual tuning and volume controls 3, a window frame 4 through which may be observed a tuning drum indicator 5, and a switch 6 for the power circuit, and by means of which the set 40 may be put into operation.

In accordance with this invention the panel 2 also supports a visible clock dial 7 in cooperation with which are a minute hand 8, an hour hand 9 and a setting pointer 10. The panel also 45 supports a switch 11 which renders operative or inoperative the time switch controlled by the clock.

The clock mechanism includes a frame 12, an electric motor having a field 13, an armature 50 14, which winds a main spring in a drum 15, an escapement mechanism 16, suitable trains of gearing for driving and regulating a shaft 17 carrying the minute hand 8 and a cylindrical shaft 18 carrying the hour hand 9. Any suitable 55 clock mechanism may be used in connection with

this invention, but for convenience I have selected a clock mechanism operated by an alternating current motor of a suitable type.

In accordance with this invention an hour hand shaft 18 is driven by a gear 19 of novel 60 construction. It is constructed of electrically non-conductive material throughout, including the hub, web and gear rack. The hub includes a cylindrical forwardly extending flange 20. A disc conductor 21 is secured to the gear 19 65 about the flange 20. Thus the disc 21 is insulated from the rest of the mechanism but rigid with the gear wheel 19 and the hour shaft 18. The gear wheel 19 is, as previously explained, driven through a train of gearing by the spring 70 drum 15 and regulated through a train of gearing by the escapement mechanism 16.

A disc or ring 22 is composed of fiber or other insulating substance and is mounted in rigid connection with the metallic disc 21 and the insulated gear wheel 19 so that the parts 22, 21, 19 and 18 rotate together.

The ring 22 is split, having one end 23 twisted or bent laterally away from and out of alignment with the opposite end 24 which is flat against the metallic disc 21. A metallic piece 25 extends between the ends 23 and 24 of the fiber ring 22 and is in permanent contact with the metallic disc 21. This metallic piece 25 projects beyond the end 23 of the ring 22 and overlaps but is 85 spaced from the end 24 of the fiber ring, as is clearly shown in Fig. 4 of the drawings. The metallic piece 25 constitutes part of the mechanism controlled by the clock mechanism for closing an electric circuit. It is now apparent that 90 the metallic piece 25 is rotated with the metallic disc 21 and with the hour shaft 18 and is insulated from the remaining mechanism of the clock.

An electric circuit wire 26 is connected at one 95 end to a power supply wire 27 and at its other end to a brush 28 arranged for continuous contact with the metallic disc 21. The brush 28 is mounted on an insulating support 29 secured to the frame 12.

It will thus be apparent that the metallic piece 25 is in continuous electrical contact with one side of an electric supply circuit.

The radio receiving set includes the chassis 30 having binding posts 31 and 32 adapted to secure 105 power supply wires for the conduction of current to operate the set. A wire 33 is connected to the post 31 and the main line wire 34 opposite the other main line wire 27. A wire 35 is secured to the binding post 32 and to the switches 6 and 11. 110

The other side of the switch 6 is secured to a wire 36 in permanent connection with the main line wire 27. The side of the switch 11 opposite the connection with the wire 35 is connected to a wire 37 permanently secured to the frame 12.

It will thus be seen that if the switch 6 is closed the set will receive a power current through the wire 33 connected to the main line wire 34, the wire 35 connected to the switch 6, and the wire 36 connected to the other main line wire 27. It will also be apparent that if the switch 6 is open but the switch 11 is closed, the set will receive a power current and will be put into operation if contact is made between the frame 12 and the 15 metallic contact piece 25.

The metallic dial 7 is secured to and in electrical communication with the frame 12. A cylindrical metallic sleeve 38 passes through the center opening in the dial and about the shaft 20 18. The pointer 10 is secured to one end of the sleeve 38 external of the dial. The sleeve 38 has an annular flange 39 to which is secured a laterally extending contact piece 40 in such position that when held stationary it will come into contact with the contact piece 25 once during each revolution of the shaft 18 by which the piece 25 is carried.

In order to secure a good electrical contact between the sleeve 38, to which is attached the 30 piece 40, and the dial 7 an annular shoulder 41 is provided on the sleeve 38 and an annular spring member 42 having legs 43 is interposed between the shoulder 41 and the dial 7. This spring member in addition to making electrical contact between the sleeve 38 and the dial 7 also acts as a detent member to secure the sleeve 38 and therefore the contact piece 40 in stationary position against the rotation with the shaft 18 which passes through the sleeve 38.

40 By moving the pointer 10 the contact piece 40 may be placed in any selected position and that position is indicated by the pointer on the dial.

It is now apparent that the contact member 40 may be moved to any desired position and 45 that position indicated by the pointer on the dial. It is also apparent that once in every revolution of the hour hand electrical contact will be made between the contact piece 25 rotated by the hour shaft and the stationary contact piece 40 which 50 may be set as desired. Thus when the switch 11 is closed current will be introduced through the wire 35 into the receiving set from the main line wire 27, the current flowing from the wire 27 through the wire 26, the brush 28, the metallic disc 21, contact piece 25, contact piece 40, collar 38, dial 7, frame 12 and the wire 37.

It is also apparent that by closing the switch 6 the receiving set may be operated independently of the timing mechanism, and by opening the 60 switch 11, the timing contacts rendered inoperative to affect the set. The switch 6 has direct cooperative relation with the timing mechanism and the circuit closer and opener operated thereby. The switch 6 constitutes a device mounted 65 in connection with the circuit of the timing mechanism whereby the operativeness of the device to be operated, which is the radio receiving set, may be quickly determined without unnecessary operation of the pointer 10 and the switch 70 mechanism controlled thereby. When it is desired to condition the mechanism for operation at a predetermined time by the timing mechanism, it is, of course, desirable to know that the mechanism will operate. This may be determined quickly by closing the switch 6 for a suf-

ficient time to energize the receiving set and thus afford indication of the fact that said receiving set is operative. Of course, if the receiving set is not operative, such condition will be indicated by the fact that it does not operate.

The time during which the receiving set will continuously operate due to the timing mechanism, is determined by the length of that part of the contact piece 25 extending beyond the end 23 of the insulating ring 22. It has been found convenient to extend the part 25 about 30° and thus the mechanism will cause continuous contact for a period of one hour. This period may be of course adjusted as desired by using a contact piece 25 of the required length.

It will thus be seen that the invention accomplishes its purpose. Mechanism has been provided to operate the time switches which is simple in construction and easy to operate.

A radio receiving set has been provided with a 95 clock having its dial conveniently displayed with the clock mechanism arranged to operate the time switch so as to turn on the radio at any predetermined time.

The setting of the timing mechanism can conveniently be accomplished. The arrangement of the time switch is such as not to interfere with the operation of the radio in the usual manner, its controls being separate from the conventional radio controls and switches.

It is obvious that the invention may be applied for the purpose of closing electrical circuits in other than radio receiving sets and its purpose is not, therefore, limited to such use.

It is also obvious that various changes may be 110 made in the details of construction within the scope of the appended claims without departing from the spirit of this invention.

I claim:

1. A time switch mechanism comprising, a 115 clock having a shaft passing through a dial and carrying an hour hand, a contact member mounted for rotation with said shaft, an electric circuit wire in electrical communication with said contact member, a collar mounted upon said 120 shaft and passing through said dial, a pointer fixed to said collar in front of said dial, a contact member mounted on the collar back of the dial, a spring detent member adapted to hold said collar in engagement with said dial, and an 125 electric circuit wire in electrical communication with said dial.

2. A time switch mechanism comprising a clock having a shaft passing through a metallic dial and carrying an hour hand, a contact member insulated from and rotated by said shaft, an electric circuit wire in electrical communication with said contact member, a collar mounted on said shaft, a device at the outer side of the dial and connected with said collar for rotating said 135 collar about said shaft, a contact member mounted on said collar at the inner side of the dial, and an electric circuit wire in electrical communication with said last named contact member.

3. A time switch mechanism comprising a clock having a shaft extending through a metallic dial and carrying an hour hand, a contact member mounted for rotation by said shaft and insulated therefrom, an electric circuit wire in 145 insulated from said shaft and in electrical communication with said contact member, a collar mounted on said shaft and rotative independently thereof, a contact member on said collar in position to be engaged and disengaged by said first 150

- contact member, an electric circuit wire in electrical communication with said second contact member, and means at the outer side of said dial for operating and adjusting said second contact member with respect to said first contact member. 80
4. A time switch mechanism comprising a clock having a shaft extending through a metallic dial and carrying an hour hand, a contact member mounted for rotation by said shaft and insulated therefrom, an electric circuit wire insulated from said shaft and in electrical communication with said contact member, a collar mounted on said shaft and rotative independently thereof, a contact member on said collar in position to be engaged and disengaged by said first contact member, an electric circuit wire in electrical communication with said second contact member, means at the outer side of said dial for operating and adjusting said second contact member with respect to said first contact member, and means in connection with and holding said second contact member from accidental displacement. 85
5. A time switch comprising a shaft carrying a time indicating hand, an electrically non-conductive gear fixed to said shaft, means for driving said gear, a brush mounted on said gear, a continuous electrical connection with said brush, a sleeve mounted on and adjustable about said shaft, a contact member mounted on said sleeve and adapted to contact with said brush, and an electrical connection in communication with said contact member. 90
6. A time switch comprising a rotary shaft, an electrically non-conductive gear attached to said shaft, means for rotating said gear and thereby said shaft, an electrically conductive brush attached to said gear, a continuous electrical connection with said brush, a sleeve supported by and rotative relative to and about said shaft as an axis, means for holding said sleeve from rotation with said shaft, means for rotating said sleeve relative to and about said shaft as an axis, a contact member mounted on said sleeve and adapted to be engaged by said brush once during each revolution of said gear, and an electrical connection in communication with said contact member. 95
7. A time switch comprising a dial member having an opening, a rotary shaft extending through said opening, a time indicating hand attached to and rotated by said shaft, an electrically non-conductive gear attached to said shaft beyond said dial member from said hand, means for rotating said gear and thereby said shaft and said hand, an electrically conductive brush mounted on said gear, a continuous electrical connection with said brush, a sleeve mounted on and rotative relative to and about said shaft as an axis and extending through said opening in said dial member, a contact member mounted on said sleeve and adapted to be engaged by said brush once during each revolution of said gear, means engaging said sleeve and said dial member holding said sleeve against rotation by said shaft and forming an electrical connection between said sleeve and said dial member, and means attached to said sleeve between said hand and said dial member for rotating said sleeve relative to and about said shaft as an axis. 100
